UNITED STATES PATENT OFFICE.

ROBERT J. PAUL AND WILLIAM C. KERSHNER, OF DAYTON, OHIO.

FORM FOR CONCRETE-SEWER CONSTRUCTION.

No. 821,824.

Specification of Letters Patent.

Patented May 29, 1906.

Application filed September 11, 1905. Serial No. 278,019.

To all whom it may concern:

Be it known that we, ROBERT J. PAUL and WILLIAM C. KERSHNER, citizens of the United States, residing at Dayton, in the county of Montgomery and State of Ohio, have invented certain new and useful Improvements in Forms for Concrete-Sewer Construction; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a collapsible form for constructing concrete sewers regardless of the dimensions or shapes of the sewer.

The object of the invention is to provide a collapsible form which admits of the entire sewer being constructed around said form before any of the parts of the form are removed, or in one operation.

To this end the form is constructed in a number of collapsible parts, either forming a circle or elliptical shape in cross-section when united.

In the drawings the form is constructed of four segments or sections which are detachably united to form a circle; but, as before stated, the transverse form of the sewer may be constructed of other shapes than that of a circle.

In the use of our improved concrete-sewer form the necessity of skilled labor is entirely dispensed with, the cost of the sewer is very materially decreased, and the work of constructing the sewer is so simplified that a small number of laborers may do the work. In removing the sections of the form after the concrete is set a single laborer is only necessary.

Preceding a more detailed description of the invention reference is made to the accompanying drawings, of which—

Figure 1 is a transverse sectional view of a concrete sewer, showing our improved collapsible form in position therein. Fig. 2 is a longitudinal sectional view looking in the direction of the horizontal arrow in Fig. 1. Fig. 3 is a similar sectional view looking downward in the direction of the vertical arrow in Fig. 1.

As before stated, the form is constructed of a plurality of matching longitudinal sec-

tions, the number of sections depending upon the diameter of the sewer. For example, Fig. 1 of the drawings shows the form constructed of four longitudinal sections which are adapted for the form of concrete sewers of any suitable diameter. It may be advisable to construct the form in a greater number of sections in order that the same may be more readily handled in constructing the sewer. We therefore do not wish to limit ourselves to the exact number of sections or parts shown in the drawings. In either event the sections are collapsible in a similar manner.

In a detailed description of the invention similar reference characters indicate corresponding parts.

The concrete sewer 1 is formed around the exterior of the form, this form consisting of a plurality of longitudinal sections each of which consists of a number of segmental ribs 2, which are united to a series of rails 3. These ribs 2 and rails 3 are secured by a suitable number of screws 4, or they may be united in any suitable manner. For example, they may be nailed together or fastened in a variety of ways, the object being to unite said rails and rib-segments rigidly. The rails 3 are united to a series of cross-braces 5 by means of notches 6 near the ends of said cross-braces, which receive the said rails. These cross-braces lie close to the ends of the ribs, but away from the sheathing, in order that they may be readily removed when collapsing the form. The abutting ends of the ribs are held in alinement when in operative positions by means of dowels 7, which are united to the upper segments or ribs and overlap the adjacent ends of the lower segments or ribs. This means prevents any lateral or side movements of the ribs when united, as shown in Fig. 1, and holds the form rigidly together.

It will be noted in Fig. 1 that the lower ends of the two lower rib-segments have a suitable space 2' between them for the insertion of a removable rail 8, which fills the space between the lower sections and extends throughout the length of the form. The lower sections should have this space between them in order that the form may be easily collapsed in removing it. This rail 8 is free from any binding contact, but lies loosely between the sections and prevents the concrete from working upwardly between

the ends of the lower sections and insures a smooth and true surface. Above this removable rail 8 and at points between the ends of the lower rib-segments there is a series of keys 9, the purpose of which is to hold each of the two lower rib-segments in position to support the upper sections. The several sections of the form are completed by uniting thereto a sheathing consisting of a plurality of laths 10, which are united to the rib-segments to form a close sheathing which extends around the form and against which the concrete is tamped into place.

The operation of forming a concrete sewer by means of our improved collapsible form is as follows: The excavation having been made, the necessary number of templets are placed therein in accordance with the grade set by the engineer. These templets are made of a form which the lower half of the sewer is to be, and when in position the concrete is placed in the excavation between the templets to a suitable height. After the concrete is thus inserted a straight-edge in the nature of a board extending from one templet to the other is used to level off the concrete to agree with the curvature of the lower half of the sewer. The templets are then removed, and the rail 8 is placed in a central position on the flow-line of the sewer. The lower sections of the form are then placed in position and the keys 9 are inserted. The lower braces 5 are next placed in position to hold the lower sections in their relative positions. After this the upper sections of the form are placed in position and are united by means of the upper braces 5. The whole form being thus placed in a rigid position, the concrete is applied and tamped around the entire form and made to unite with the concrete which has been placed below until the entire sewer is completed to the thickness and dimensions required. After the concrete has set the form is easily removed by first removing the keys 9, which are removable by knocking upon them with a hammer. The rail 8 is then free to be removed, which affords sufficient space for the removal of the lower sections of the form. The upper sections are then easily separated by removing their cross-braces 5, and the whole form is

collapsed quickly and in a manner which permits its removal by a single person.

Having described our invention, we claim—

1. A form for concrete-sewer work, consisting of sections when brought together forming a circle in cross-section, said sections engaging each other, and held by horizontal cross-braces extending from one side to the other of the structure, the two lower sections having inserted between them a series of removable keys which, when in position, serve to rigidly lock the sections together, and a rail longitudinally insertible below said keys within the space between the longitudinal edges of the lower sections, substantially as specified. 55

2. A form for concrete-sewer work consisting of a series of four sections which, when brought together, complete a circle in cross-section, horizontal cross-braces uniting the sections adjacent to the horizontal abutting edges of said sections, a rail insertible longitudinally within the space between the lower sections and completing the circle of the assembled sections, and a series of blocks within said space above the rail and serving to tie the sections together during the formation of the sewer construction, substantially as specified. 70

3. A form for concrete-sewer construction, consisting of a series of sections assembled to form a circle in cross-section, two horizontal cross-braces joining the opposite sections adjacent to their horizontal abutting edges, 85 said cross-sections engaging the longitudinal rails of said sections, a loose rail insertible longitudinally within the space between the lower sections and completing the circular form of the structure, and a series of blocks 90 interposed between the edges of the lower sections above the loose rail and serving to key the assembled sections during the construction of the sewer, substantially as described. 95

In testimony whereof we affix our signatures in presence of two witnesses.

ROBERT J. PAUL.

WILLIAM C. KERSHNER.
